UNITED STATES PATENT OFFICE.

HARRISON H. BROWN, OF FOND DU LAC, WISCONSIN.

HOLDBACK ATTACHMENT FOR VEHICLES.

SPECIFICATION forming part of Letters Patent No. 628,301, dated July 4, 1899.

Application filed December 29, 1898. Serial No. 700,636. (No model.)

To all whom it may concern:

Be it known that I, HARRISON H. BROWN, a citizen of the United States, residing at Fond du Lac, in the county of Fond du Lac and State 5 of Wisconsin, have invented certain new and useful Improvements in Holdback Attachments for Vehicles; and I do hereby declare the following to be a full, clear, and exact description of the invention, such as will enable 10 others skilled in the art to which it appertains to make and use the same.

This invention relates to improvements in holdback attachments for the thills of vehicles, and has for its object to provide a simple, 15 cheap, and durable safety attachment of this character adapted to hold the holdback or breeching strap of the harness securely against displacement, but in such a manner as to permit of the ready release of the same to allow 20 the draft-animal to move out of the thills should the traces break or become disconnected, and thus prevent injury to the vehicle or occupants thereof.

A further object is to provide a holdback 25 attachment which is designed to hold the strap at the proper angle relatively to the thills and to prevent undue play of the strap and wear thereon and objectionable strain on said attachment, and also to provide a guard to 30 shield the holdback attachment from injury or extraneous shocks or blows and prevent the tail of the draft-animal and the side edges of a fly-netting, when the latter is used, from catching in the latch or hook of the holdback.

35 With these and other minor objects in view the invention consists of certain novel features of construction, combination, and arrangement of parts, which will be hereinafter more fully described, and particularly pointed 40 out in the appended claims.

In the accompanying drawings, forming a 45 part of this specification, Figure 1 is a side view of a portion of a vehicle-thill having my improved holdback attachment applied thereto. Fig. 2 is a perspective view of the holdback-iron, showing the guard in broken lines. Fig. 3 is a bottom plan view of the parts as 50 shown in Fig. 1. Fig. 4 is a cross-section through the thill, looking toward the outer end of the hook-arm.

Referring now more particularly to the drawings, wherein like reference-letters design-

5 nate corresponding parts throughout the several views, A represents a portion of a vehicle-thill, and B the rear end of the holdback-iron, which consists of a comparatively broad flat plate attached to the under side of the thill by screws or other suitable fastening devices. Projecting forwardly from this plate is a hook-arm C, the front portion of which 60 lies sufficiently below the under side of the thill to admit the folded end of the holdback-strap D of the harness or an eye on the end thereof, and the upper face of this front portion of the arm is recessed to form a longitudinal chamber E, one side wall of which is preferably cut away, as at f, to provide a clearance-opening through which any dust or dirt which enters and clogs the chamber may drop out or be readily removed. Arranged 65 in this chamber is a curved latch G, pivoted at its rear end g to the arm and having its outer end g' curved downwardly into the forward part of the chamber to permit of the insertion of the holdback-strap between the 70 hook-arm and thill and its central portion g² normally held pressed against the under side of the latch.

The hook-arm extends parallel with the thill, 75 adjacent to the inner edge of the same, and is 80 connected at its rear end to an extension h, projecting from the outer edge of the front portion of the plate B, by an obliquely-arranged inwardly-extending shoulder I, which 85 serves as a bearing for the holdback-strap D to hold the latter at the proper angle—namely, substantially at an oblique angle to the thill—and the front edge of this shoulder is rounded 90 to provide a broad bearing for and prevent cutting of the strap or undue wear thereon. In practice the folded or looped end of the strap is engaged with the front end of the 95 hook-arm and passed back until it engages the oblique shoulder, the latch opening under the pressure of the upper stretch of the strap to permit of the passage of the latter and then closing to retain the same in position against casual displacement. When this is done, it will be seen that the strap will be held from working forwardly under ordinary 100 conditions by the angular arrangement of the hook-arm at its junction with the shank and from working rearwardly by the said extension h of the rear attaching-plate of the hold-

back-iron. By this means undue play and wear of the strap are prevented and excessive side strain on the attaching-plate of the hold-back-iron avoided. The inner surface of the extension h and front edge of the rear attaching-plate B are preferably beveled to allow the strap to snugly seat itself and avoid the formation of angles therein. A guard is employed to shield the holdback-iron against injury by extraneous shocks or blows and prevent the tail of the draft-animal or side edges of a fly-netting from catching in the hook-arm and latch. This consists of a rod or bar J, having upwardly-bent ends k and k' arranged in alinement, and the former being secured directly to the under side of the thill in advance and to one side of the front end of the hook-arm through an opening k^2 in the attaching-plate of the holdback-iron and fitted in a socket or opening in the thill. The central body portion of the guard is deflected laterally toward the inner side of the thill and is arranged immediately below the hook-arm, and at its rear it has an angular extremity k^3 which lies below the front edge of the attaching-plate B just inside of the extension thereof and oblique bearing-shoulder and serves as a stop to prevent the strap from sagging downward or bulging out to an objectionable extent. The end k' of the guard also acts in conjunction with the bearing-shoulder and rear end of the hook-arm to limit the lateral movement of the strap. The guard as constructed effectually shields the parts of the holdback-iron and prevents the tail of the horse or side edges of a fly-netting from wrapping around or being caught by the hook-arm or latch thereof.

The manner in which the holdback is connected and retained in position has been heretofore described, and it will be readily perceived that under ordinary conditions the strap cannot become accidentally disengaged. When the traces are released or become broken or disconnected, however, the forward pull on the strap causes the latter to clear the oblique shoulder and the latch yields to permit of the withdrawal of the strap, thus allowing the draft-animal to move out from the thills. By this means injury to the vehicle or occupants thereof is prevented when the

traces become disconnected and the draft-animal bolts.

It will be understood, of course, that changes in the form, proportion, and minor details of construction may be made within the scope of the invention without departing from the spirit or sacrificing any of the advantages thereof.

Having thus described the invention, what is claimed as new is—

1. A holdback attachment for vehicle-thills provided at its rear end with an attaching-plate and at its front end with a chambered hook-arm arranged in line with one side of the plate and connected to the opposite side thereof by an obliquely-arranged bearing-shoulder, and a spring-actuated latch arranged in the chamber of the arm and adapted to bear against the thill. 70
2. The combination with a thill, of a holdback attachment therefor provided at its rear end with a plate secured to the under side of the thill and having an extension projecting forwardly from the outer side thereof, a chambered hook-arm extending parallel with the thill adjacent to the inner edge of the latter, an obliquely-arranged bearing-shoulder connecting the rear end of the arm to said extension, and a spring-actuated latch pivoted in the chamber of the arm and bearing adjacent to the under side of the thill, substantially as described. 75
3. The combination, with a vehicle-thill, of a holdback attachment therefor, comprising a rear attaching-plate secured to the under side of the thill, and provided with an extension projecting forwardly from the outer front edge thereof, a chambered hook-arm extending parallel with the thill adjacent to the inner edge thereof, an obliquely-arranged bearing-shoulder connecting the rear end of the hook-arm to the extension, and a guard secured to the under side of the thill and shielding said parts, substantially as described. 85 90 95

In testimony whereof I affix my signature in presence of two witnesses.

HARRISON H. BROWN. [L. S.]
